DEVICE FOR MOVING THE LAY OF
MECHANICAL WEAVING LOOMS

Otto Wittmers, Cologne-on-the-Rhine, Germany

Application October 17, 1934, Serial No. 748,670
In Germany October 19, 1933

8 Claims. (Cl. 139—190)

Devices for moving the lays of mechanical weaving looms are known, in which the lay sword bearing the shuttle race and the abutment reed carries at its upper end a double-armed lever which is hinged to it and has two arms of unequal length forming between them an obtuse angle open in the direction towards the driving shaft.

The upper arm of that two-armed lever which is the shorter one is joined to the pivot of the crank of the driving shaft by the intermediary of a connecting rod, whereas to the end of the longer arm of said lever is hinged the rod of an eccentric ring, the disk of which is secured to the driving shaft.

The object of this known arrangement and combination of parts is to drive the shuttle through the shed with a reduced resistance to motion and to obtain thereby an increase in the number of revolutions of the driving shaft and, therefore, also an increase in the performance of the weaving loom.

Building this device into existing looms is often connected with difficulties. Many looms lack the rotatory surfaces for the attachment of such an eccentric disk (in the following part of this specification termed control eccentric disk) on the driving shaft.

For the above-mentioned reason I propose to utilize, as is done in the present invention, the crank pivot of the driving shaft as bearing member for two hinges or joints, that is to say, to use said pivot as support for that end of the connecting rod which is hinged to the shorter arm of the two-armed lever of the lay sword, as well as support for the eccentric disk of the control eccentric.

This idea of invention can practically be easily realized in this way that the eccentric disk is made multi-parted, at least two-parted, and is provided with a sleeve-like lateral extension which is placed upon the crank-pin of the driving shaft and serves as a rotary bearing for the connecting rod that is hinged to the shorter arm of the double-lever, this arm being, in turn, hinged to the lay sword.

It is possible to make the circumferential outer surface of said sleeve-like extension eccentric in such a degree as may be desired or required, whereby the further possibility is presented of regulating the extent of the angular motion of the said double-lever whereby the stroke of the lay can be increased or decreased, as may be necessary. Besides, owing to the smallness of the space required, the arrangement also permits pro-

viding such weaving looms therewith in which there is located below the crank shaft a transverse bar that would normally prevent the attachment of a separate control eccentric.

Finally, the twofold utilization of the supporting place for the joints of the connecting rod and of the control eccentric permits also a better and more effective arrangement of means serving to obviate the necessity of reducing too strongly the speed of the moving mass of the lay towards the end of its motion, whereby, if the braking surpasses a certain normal limit, parts of the loom are likely to be destroyed. As now the disk of the control eccentric is arranged laterally from one of the crank legs of the driving shaft, the joint between the eccentric rod and the longer arm of the double-lever of the lay sword permits one to render the shape of said joint variable, in such a manner, that in the case of the braking power exceeding a certain normal measure the momentum can be annihilated in the moving mass on a long braking path.

The invention is illustrated diagrammatically and by way of example in the accompanying drawing in which Figure 1 is a side-view of the known lay drive shown for the purpose of comparison between what is old and what is new. Figure 2 is a side-view of an eccentric disk designed according to this invention, in combination with some other parts, the eccentric ring being omitted, and the disk being located upon the crank pivot of the driving shaft. Figure 3 is a transverse section in the plane I—I of Fig. 2. Figure 4 is a side-view of the entire arrangement and combination of the parts constituting my invention. Figure 5 is a plan of the parts shown in Fig. 4. Figure 5^a is a transverse section in the plane III—III of Fig. 4, the parts shown in the left-hand half of Fig. 4 being omitted, and one of the parts (the sleeve left-hand from the eccentric disk) being slightly modified. Figure 5^b shows a modification of the arrangement and combination of parts shown in the lowermost portion of Fig. 4. Figure 6 is a modification of the arrangement and combination of parts shown in the left-hand portion of Fig. 4. Figure 7 is a front-view of this modification, seen in the direction from the right to the left in Fig. 6, and Fig. 8 shows another modification drawn to a reduced scale.

In the drawing, 4 (Figs. 1, 4 and 5) denotes one of the lay swords, and 6, 7 (Figs. 1 and 4) denotes a bell-crank lever comprising a shorter arm 6 and a longer arm 7. This lever is hinged at 5 to the lay sword, and the lever arm 6 is

jointed at 8 to one end of the connecting rod 10. This arrangement and combination of parts exists at each lay sword. Only one is shown in the drawing.

5 In the improved device illustrated in Figs. 2-5^a, the other end (10^a, Fig. 4) of the connecting rod 10 embraces a sleeve-like projection of the eccentric disk 14, 14^a which is two-parted, comprising a larger part 14 and a smaller part 14^a, and 10 is located upon the pivot 12 of the crank 13 of the shaft 15, as is seen best in Fig. 5^a. 18^a (Fig. 4) denotes the plane in which the two parts of the eccentric disk abut against one another, and this plane extends through the axis of the 15 pivot 12. Where the parts 14 and 14^a contact with one another, there they are provided with lugs 20 that are firmly connected with one another by nut bolts, whereby, of course, also the two parts of the eccentric disk are securely connected with one another. The eccentric disk is 20 integral with the sleeve 18 wherefrom follows that also this sleeve is two-parted, the one part being integral with the disk-part 14 and the other part being integral with the disk-part 14^a. 25 The free end of the sleeve 18 has rim or flange 18^b (Figs. 3 and 5^a) likewise, of course, bipartite.

The eccentric disk 14, 14^a is surrounded with the ring 11^a which has at its inner circumference a groove that is engaged by an annular projection of the outer circumference of the disk. In view of this coupling of the eccentric disk with the appertaining ring it is a matter of course that also said ring is two-parted; the two parts 35 are connected with one another by screw-bolts 19 (Fig. 4). From the lower half of the said ring extends a slotted arm 11 which will be dealt with hereinafter.

In order to prevent turning of the eccentric 40 upon the crank pivot 12, lugs 22 (Fig. 4) are provided which extend from that face of the disk portion 14 that is located counter to the sleeve 18 and hold each a bolt 23 which abut at one side of the crank 13.

45 The free end of the arm 11 which projects forth from the eccentric ring 11^a has an oblong slot 25 (Fig. 4) through which extends a bolt 9. The arm 11 crosses the longer arm 7 of the bell-crank lever 6, 7; said lever-arm has a slot 7^b in which 50 slides a block 32 (Fig. 5). The bolt 9 extends also through this block and is between the arms 7 and 11 provided with a spacing disk 9^b (Fig. 5) which maintains the proper distance between said arms. Both ends of the bolt 9 are threaded; 55 the one thread engages a correspondingly threaded bore in the block 32 and the other thread is provided with a nut 31 (Fig. 5). It will be obvious that the block 32 can be adjusted in the slot of the lever-arm 7 and that the bolt 9 can be shifted in the slot of the arm 11 of the eccentric and that, therefore, the arms 7 and 11 can be adjusted with respect to one another and can be connected with one another in their 60 adjusted position. By shifting the block 32 in the lever-arm 7, the effective length of this arm can be varied and by displacing the bolt 9 in the arm 11 the stroke of the eccentric disk, as well as the angle between the crank 13 and the eccentric disk can likewise be varied.

70 In the modification shown in Fig. 5^b the block 30^a is located in the slot 25^a of the arm 11^a, and shiftable in this slot whereas there is no slot in the arm 7^a. At the free end of the arm 11^a is an adjusting bolt 27, in the block 30^a is a bolt 26, and between this bolt and the bolt 27 is a

helical tensile spring 28. The particular effect of this modified arrangement and combination of parts is that it prevents, in the case of a greatly increased number of revolutions of the shaft 15, an excessive influence of the moving masses when 5 the lay is moved into the fell of the cloth. The length of the braking path in which the force acting in the reciprocating lay, in the normal construction of the same, is to be depleted is very short, in that it amounts generally only to 10 about from 5 to 7 mm. If in a loom provided with the device shown in Fig. 5^b the number of revolutions is increased, the superfluous force of the moved mass is intercepted by the spring 28, which constitutes a safety member, in that 15 the surplus of energy is consumed.

A link motion that comprises a slotted member and a block therein, as in Figs. 4 and 5^b requires, of course, oiling. This can be obviated if, as in the further modification shown in Figs. 6 and 7, 20 the bell-crank lever 6^a, 7^a co-operates with a one-armed lever 7^c supported on the pivot 5^a of the lever 6, 7. There is likewise a helical tensile spring 28^a, as in Fig. 5^b, and there is also an adjusting bolt 27^a for the same, but this bolt is located in the free end 7^d of the lever 7^c and the upper end of said spring is attached to the lever arm 7^a with which it is connected by a pin 26^a. At the upper end of the lever 7^c, laterally from the pivot 5^a, is a lateral projection 7^e which is 30 located between the arms of the bell-crank lever 6^a, 7^a, without normally being in contact with either of them, in that this is prevented by the spring 28^a. But if the force acting in the moving lay should become abnormally strong, the 35 spring 28^a will be expanded until the arm 7^a of the bell-crank lever contacts with the projection 7^e of the lever 7^c. The surplus of the force in question is, thus, intercepted and annihilated by the spring 28, so that a destruction of the 40 loom parts concerned is prevented.

Referring, finally, to the modification shown in Fig. 8, the position and the shape of the bell-crank lever 6, 7 differs from the position and the shape of the bell-crank lever 6, 7 in Fig. 6, in 45 that its arm 6 extends laterally instead of upwardly and its arm 7 extends downwardly instead of laterally. The auxiliary lever 7^c is in this modification supported not upon the same pivot on which the bell-crank lever 6, 7 is supported, as is the case in Fig. 6, but it is supported upon a separate pivot 5^a provided upon the arm 7 of the bell-crank lever. Laterally from this pivot (left-hand from it in Fig. 8) the lever-arm 7 is provided with a pivot-like projection 7^f 55 which is in contact with the middle portion of a plate spring 28^b consisting preferably of a plurality of lamellæ. The upper end of this spring bears against a face 6^b of the lever-arm 6, and the lower end of said spring engages a recess 7^g 60 provided in the lower end of the auxiliary lever 7^c. On the right-hand side of this lever-arm is another recess 7^f engaged by the lower end of another plate-spring 28^a likewise composed preferably of a plurality of lamellæ. The middle portion 65 of this spring contacts with the head-portion 7^h of the lever 7^c.

The body-portions of the levers 6, 7 and 7^c are shown in section.

8 denotes the bolt connecting the lever-arm 6 70 with the connecting rod 10 of Fig. 4, and 9 denotes the bolt connecting the auxiliary lever 7^c with the arm 11 of the eccentric, likewise as in Fig. 4.

As long as the forces acting upon the lever- 75

5 arms 6, 7 and 7^c do not surpass a certain normal strength, they are and remain in the position shown in Fig. 8, in which position the spring 28^a is kept under a certain preliminary tension by means of the head-portion 7^h of the lever 7^c. When, however, the forces acting upon the said levers surpass that certain normal strength, their position relatively to one another changes, in that the lever 7^c is turned on the pivot 5^a, in consequence whereof the head 7^h of the lever 7^c bends the spring 28^a more so as to increase its tension; at the same time also the spring 28^b is bent more whereby the tension also of this spring is increased and the forces to be annihilated are 10 15 20 25 30 35 40 45 50 55 60 65 70 75 80 85 90 95 100 105 110 115 120 125 130 135 140 145 150 155 160 165 170 175 180 185 190 195 200 205 210 215
